[57] CLAIM

The ornamental design for a bathtub pillow, as shown and described.

DESCRIPTION

FIG. 1 is a perspective view of a bathtub pillow showing my new design, which has been mounted on a bathtub;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side being the mirror image thereof; and

FIG. 7 is a sectional view thereof taken on line 7—7 in FIG. 2 in the direction of the arrows.

The fragmentary broken line representation of a bathtub in FIG. 1 is for purposes of illustration only.

FIG. 1

FIG. 3

FIG. 4
